R. W. MAC GOWAN, OF NEW YORK, N. Y.

Letters Patent No. 72,059, dated December 10, 1867.

IMPROVEMENT IN REGISTER-POINTS FOR PRINTING-PRESSES.

The Schedule referred to in these Letters Patent and making part of the same.

TO ALL WHOM IT MAY CONCERN:

Be it known that I, R. W. MAC GOWAN, of the city, county, and State of New York, have invented a new and useful Improvement in Printing-Pointers; and I do hereby declare that the following is a full, clear, and exact description thereof, which will enable others skilled in the art to make and use the same, reference being had to the accompanying drawings, forming part of this specification.

This invention relates to a new and improved application of pointers to printing-presses for registering the sheets of paper as they are fed to the press. Hitherto these pointers have been operated automatically from the moving parts of the press, allowed to remain in an elevated or nearly upright position, and through the sheet, until the fingers or nippers of the cylinder arrive in proper position to grasp the sheet, at which time the points are drawn down, and the sheet released, so that it may be connected with the cylinder and rotated with the same in order to receive the impression.

My improvement consists in applying a spring, or an equivalent weight, to the pointers; the latter being pivoted at their lower ends, or attached to axes, and all constructed and arranged in such a manner that the pointers will hold the sheets properly in position on the feed-board, and the nippers of the cylinder allowed to draw the sheet off from the points, on account of the latter yielding or being allowed to be drawn down under the slight pull of the sheet, the spring or weights throwing the points back to their original position as soon as the sheet is withdrawn. By this arrangement all mechanism for operating the pointers is avoided, and a very simple and economical pointing or registering-device obtained. In the accompanying sheet of drawings—

Figure 1 is a plan or top view of my invention.

Figure 2 a vertical section of the same, taken in the line $x x$, fig. 1.

Similar letters of reference indicate corresponding parts.

A represents a metal tube, having a screw-thread, a , cut on the lower part of its exterior, and provided with a cap-plate, b , at its top, which projects beyond the tube, being somewhat greater in diameter than the latter, as shown in fig. 2. The cap-plate b has an oblong slot, c , made in it, through which a pointer, B , passes. This pointer, at its lower end, is fitted in a small shaft, d , which is within the tube A , the ends of the shaft being allowed to turn freely in the side of the tube. To the lower end of the pointer B , and side of the tube, there is attached a spiral spring, e , and this spring has a tendency to keep the pointer in an upright position or against the outer end of the slot c , as will be fully understood by referring to fig. 2. The tube A is fitted in a circular opening made in the feed-board, shown in red, the cap-plate b fitting "flush" in the upper surface of the feed-board, and the tube firmly secured in position by a nut, C , on its lower end. Any proper number of these pointers may be fitted in the feed-board; there should be two at least, one at each side near its inner end. The pointers are readily drawn over, as shown in blue, fig. 2, under the pull of the sheet, as the nippers grasp the latter, and allow the sheet to pass freely off from them, the springs e throwing the pointers back to penetrate a succeeding sheet as soon as the nippers draw the preceding sheet off. Thus, by this simple means, all mechanism for operating the pointers is avoided. They are self-operating, and consequently will not be liable to get out of repair or become deranged by use.

I claim as new, and desire to secure by Letters Patent—

1. The pivoted or jointed pointer B , having a spring or equivalent weight attached, and arranged to operate in the manner substantially as and for the purpose set forth.
2. I further claim the tube A , provided with the slotted cap-plate b and the nut C , when used in connection with the pointer, for the purpose specified.
